CANDLE SHAPER

Joseph Leigh Smith, 630 Lenox,
Glen Ellyn, Ill. 60137

Filed Aug. 8, 1974, Ser. No. 495,547

Term of patent 14 years

Int. Cl. D8—03

U.S. Cl. D8—98

FIG. 1 is a front elevational view of a candle shaper showing my new design;

FIG. 2 is a right side elevational view of the candle shaper shown in FIG. 1;

FIG. 3 is a left side elevational view of the candle shaper shown in FIG. 1;

FIG. 4 is a top plan view of the candle shaper of FIG. 1; and

FIG. 5 is a rear elevational view of the candle shaper of FIG. 1.

I claim:

The ornamental design for a candle shaper, as shown.
